CLAIM

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

1.8 : Partially open perspective

1.9 : Partially open perspective

The bracelet comprises a curved rectangular band, with its ends overlapping to form a ring; a first end of the band has a transverse opening, and the other or second end has a transverse appendage, having a longitudinal opening and is folded, in the closed condition of the bracelet, over the first end; the second end of the band is provided on its outer surface with a clasp comprising an annular pivoting locking element, which, in the closed condition of the bracelet, extends through and beyond the opening of the first end and the opening of the appendage of the second end.

1 Claim, 9 Drawing Sheets
